UNITED STATES PATENT OFFICE

2,049,813

TURNTABLE

Albert F. MacDonald, Leetsdale, Pa.

Application May 21, 1934, Serial No. 726,805

7 Claims. (Cl. 104—35)

This invention relates to turntables such as are used by railroads for turning locomotives and by other industries for turning loads of various sorts.

There are two types of these turntables. One is the cantilever type in which the load is supported entirely by a centrally located pivot. The other and more modern one is the continuous type wherein the load is divided between a centrally located pivot and trucks riding on a circular rail arranged concentrically about this pivot. Since the first mentioned type must necessarily also include a circular rail, it is possible to effect its conversion to the second mentioned type by substituting heavier trucks in such a manner that they carry a part of the load formerly concentrated on the pivot.

One of the objects of the present inventor is to provide a turntable of the continuous type which is of such construction that the load may be distributed between the three supporting points to better advantage than is possible in the case of turntables of previously known construction. Another object is to provide an improved method of converting a cantilever type turntable to a continuous type turntable so that it is unnecessary to cut the main girders. Other objects may be inferred.

Figure 1 shows the top of a turntable constructed according to the present invention as it appears when a new or original installation.

Figure 2 is a longitudinal section from the line II—II in Figure 1.

Figure 3 is an enlarged cross-section from the line III—III in Figure 2.

Figures 4 and 5 show the top and longitudinal section of the end of a conventional cantilever type turntable.

Figure 6 shows the conversion of this turntable to the continuous type in accordance with the present invention.

The figures illustrating the example of a new installation show a turntable including interconnected continuous main girders 1 arranged in spaced parallel relationship. A pivot 2 centrally supports these main girders, and a circular pit rail 3 is arranged beneath these main girders concentrically about this pivot. Loading girders 4 extend over the rail 3 from the outsides of the main girders 1. Trucks 5 ride on the pit rail 3 completely outside and away from under the main girders 1 and support the latter through the loading girders 4. Two of the trucks, one at each end of the main girders 2, may be provided with a means for powering the same, such as the electric motors 6 which may be geared to the

truck wheels in any suitable manner. The diameter of the pit rail 3 is substantially less than the lengths of the main girders 1.

The various details of construction involved in the arrangement of the main girders 1, the arrangement of the loading girders 4 and the provision of the trucks 5 are not disclosed, for the reason that they may be easily supplied by any structural steel engineer.

To illustrate the new method the drawings show a portion of a cantilever type of turntable including main girders 7, pit rail 8 and truck 9, the latter being arranged directly beneath the main girders 7 in the conventional manner. It is to be understood that the trucks 9 are only intended to support the main girders 7 during the time a locomotive is being driven onto the turntable, and that the usual centrally located pivot carries the entire load during the turning operation.

According to the new method this turntable is converted by removing the trucks 9; attaching short girders 10 to the main girders 7 so as to extend away from the outsides thereof horizontally over the pit rail 8, arranging trucks 11, of suitable strength, on the rails 8 completely outside and away from under the main girders 7 and under the short girders 10, and then interconnecting the trucks 11 and the short girders 10 so that the load from the main girders 7 is transmitted to the trucks 11 by way of the short girders 10. One of the trucks 11 at each of the ends of the main girders 7 may be powered by means of an electric motor 12 driving one of the wheels of the trucks through suitable gearing. No details of construction are included for the reason that they depend upon the fancy of the designer of the conversion parts.

In all cases, one of the primary features of the invention is the positioning of the load carrying trucks completely outside and away from under the ends of the main girders, the load being transmitted by short loading girders extending from the outsides of the main girders over the pit rail and arranged in connection with the trucks. It is apparent that the invention is applicable to both deck-type and through-type turntables.

I claim:

1. A turntable including the combination of interconnecting laterally spaced main girders, a pivot centrally supporting said main girders, a circular rail arranged beneath said girders concentrically about said pivot, loading girders extending over said rail from the outsides of said main girders, said loading girders being in con-

- nection with said main girders, and trucks riding said rail and supporting said main girders through said loading girders, said trucks being in connection with said loading girders.
5. 2. A turntable including the combination of interconnecting laterally spaced main girders, a pivot centrally supporting said main girders, a circular rail arranged beneath said girders concentrically about said pivot, loading girders extending over said rail from the outsides of said main girders, said loading girders being in connection with said main girders, and trucks riding said rail completely outside and away from under said main girders and supporting the latter through said loading girders, said trucks being in connection with said loading girders.
10. 3. A turntable including the combination of interconnecting laterally spaced main girders, a pivot centrally supporting said main girders, a circular rail arranged beneath said girders concentrically about said pivot, loading girders extending over said rail from the outsides of said main girders, said loading girders being in connection with said main girders, and trucks riding said rail and supporting said main girders through said loading girders, the diameter of said rail being substantially less than the lengths of said main girders and said trucks being in connection with said loading girders.
15. 4. A turntable including the combination of interconnecting laterally spaced main girders, a pivot centrally supporting said main girders, a circular rail arranged beneath said girders concentrically about said pivot, loading girders extending over said rail from the outsides of said main girders, said loading girders being in connection with said main girders, and trucks riding said rail completely outside and away from under said main girders and supporting the latter through said loading girders, the diameter of said rail being substantially less than the lengths of said main girders and said trucks being in connection with said loading girders.
20. 5. A turntable including the combination of interconnecting continuous main girders arranged in spaced parallel relationship, a pivot centrally supporting said main girders, a circular rail arranged beneath said main girders concentrically about said pivot, loading girders extending over said rail from the outsides of said main girders, said loading girders being in connection with said main girders, trucks riding said rail completely outside and away from under said main girders and supporting the latter through said loading girders, and means for powering at least one of said trucks, said trucks being in connection with said loading girders.
25. 6. A turntable including the combination of interconnecting continuous main girders arranged in spaced parallel relationship, a pivot centrally supporting said main girders, a circular rail arranged beneath said main girders concentrically about said pivot, loading girders extending over said rail from the outsides of said main girders, said loading girders being in connection with said main girders, trucks riding said rail completely outside and away from under said main girders and supporting the latter through said loading girders, the diameter of said rail being substantially less than the lengths of said main girders and said trucks being in connection with said loading girders.
30. 7. A method of converting a cantilever type of turntable to a continuous type, including attaching short girders to the main girders of said turntable so as to extend away from the outsides thereof horizontally over the latter's pit rail, arranging trucks on said pit rail completely outside and away from under said main girders and under said short girders, and interconnecting said trucks and said short girders so that the load from said main girders is transmitted to the former by way of the latter.
35. 8. A turntable including the combination of interconnecting continuous main girders arranged in spaced parallel relationship, a pivot centrally supporting said main girders, a circular rail arranged beneath said main girders concentrically about said pivot, loading girders extending over said rail from the outsides of said main girders, said loading girders being in connection with said main girders, trucks riding said rail completely outside and away from under said main girders and supporting the latter through said loading girders, and means for powering at least one of said trucks, the diameter of said rail being substantially less than the lengths of said main girders and said trucks being in connection with said loading girders.
40. 9. A turntable including the combination of interconnecting continuous main girders arranged in spaced parallel relationship, a pivot centrally supporting said main girders, a circular rail arranged beneath said main girders concentrically about said pivot, loading girders extending over said rail from the outsides of said main girders, said loading girders being in connection with said main girders, trucks riding said rail completely outside and away from under said main girders and supporting the latter through said loading girders, the diameter of said rail being substantially less than the lengths of said main girders and said trucks being in connection with said loading girders.

ALBERT F. MACDONALD.
